WEIGHTING DEVICE

Jacob Häfeli, Uster, Switzerland, assignor to
 Aktiengesellschaft Joh. Jacob Rieter & Cie.,
 Winterthur, Switzerland

Application August 10, 1942, Serial No. 454,315
 In Germany August 1, 1941

2 Claims. (Cl. 19—135)

This invention relates to a device for weighting the press rollers of draw frames in spinning machines.

According to prior arrangements of this character, the press rollers are weighted on one machine side by a means containing a pneumatic or hydraulic pressure medium subjected to regulatable pressure. As spinning machines are as a rule double-sided, weighting is usually effected by continuous weights disposed between the two sides of a draw frame, the ends of the weights being engaged by draw rods which transmit the weight to the draw frames.

The present invention constitutes an improvement over the prior arrangements in so far as weighting of the press rollers on several or all drawing sections of both machine sides is brought about by a single means containing a pneumatic or hydraulic medium subjected to regulatable pressure. This construction affords the advantage that the means for exerting pressure may be placed under the cover of the machine and that only a single means is required for the whole machine. Compared with the known arrangement, this involves a considerable saving and simplifies also the construction of the draw frames. Furthermore, the innovation can be installed in existing machines to get rid of the weights, so that a lot of material can be saved both in new and rebuilt machines.

The invention is illustrated by way of example in the accompanying drawing, in which

Figure 1 is a section of the weighting means; Fig. 2, a plan thereof; and

Fig. 3, a detail view of the roller weighting.

Between the roller beams 1 a cover 2 is provided. The beams 1 are supported by spring pieces 3 the connecting members 4 of which sustain a U-shaped section iron 5 which extends over the entire length of the machine and contains in its cavity a hose 6 for the reception of a pneumatic or hydraulic pressure medium. The hose 6 is sealed at both ends and fitted with means for regulating pressure. Pressure plates 7 resting on the hose 6 act on a double lever 8 whose ends are articulated to draw rods 9 mov-

ably engaging a draw hook 10. The hook 10 is connected with weighting saddles 11 on the rollers 12, 13. Supporting rods 14 are secured on each side of the machine under the ends of the lever 28.

5 The device operates as follows:

The hydraulic or pneumatic medium in the hose 6 is put under pressure, so that the hose will expand and force the pressure plates 7 10 downwardly. This pressure is transmitted to the double lever 8 and thus to the right and left of the machine, with the aid of the rods 9 and hook 10, to the saddles 11 and by the latter to the press rollers 12, 13. If a draw frame is to be relieved on one side, it is only necessary to lift off the hook 10 with the saddles 11 to lower one end of the double lever 8 until it rests on the adjacent supporting rod 14; the other side remains under the same pressure as before.

20 What is claimed is:

1. A device for weighting the press rollers of draw frames in spinning machines on both sides thereof, comprising a U-shaped section iron disposed under the machine cover between the draw frames on both machine sides, a hose sealed at both ends and arranged in the cavity of said section iron for the reception of a pressure medium, and means connecting said hose with the press rollers of a draw frame.

2. A device for weighting press rollers of draw frames in spinning machines on both sides thereof, comprising a U-shaped section iron disposed under the machine cover between the draw frames on both machine sides, a hose sealed at both ends and arranged in the cavity of said section iron for the reception of a pressure medium, pressure plates supported by said hose, a double lever acted upon by said pressure plates, draw rods articulated to the ends of said lever, a

35 draw hook engaged by said rods, said hook being connected with saddles resting on the press rollers, and bars on each machine side for supporting said double lever.
